Primary Examiner—Carol Rademaker(74) *Attorney, Agent, or Firm*—Lars S. Johnson; James D. Ryndak(57) **CLAIM**

The ornamental design for a bottle portion, as shown and described.

DESCRIPTION

FIG. 1 is a perspective view of a first embodiment of a bottle portion showing the new design;

FIG. 2 is a front elevational view thereof, the rear elevational view being identical except for the unclaimed threads;

FIG. 3 is a left side elevational view thereof, the right side elevational view being identical except for the unclaimed threads;

FIG. 4 is a top plan view thereof;

FIG. 5 is a bottom plan view thereof;

FIG. 6 is a perspective view of a second embodiment of a bottle portion showing the new design;

FIG. 7 is a front elevational view thereof, the rear elevational view being identical except for the unclaimed threads;

FIG. 8 is a left side elevational view thereof, the right side elevational view being identical except for the unclaimed threads;

FIG. 9 is a top plan view thereof; and,

FIG. 10 is a bottom plan view thereof.

The stipple shading shown in FIGS. 1-5 represents a textured surface.

The broken line showing in the drawings are for environmental purposes only and form no part of the claimed design.
